UNITED STATES PATENT OFFICE.

ROLLIE B. PAGEOL, OF OAKLAND, CALIFORNIA, ASSIGNOR TO AMERICAN CHAIN COMPANY, INC., OF BRIDGEPORT, CONNECTICUT, A CORPORATION OF NEW YORK.

BUMPER-BAR CLAMP.

Application filed April 10, 1923. Serial No. 631,078.

To all whom it may concern:

Be it known that I, ROLLIE B. PAGEOL, a citizen of the United States, residing at Oakland, county of Alameda, and State of California, have invented new and useful Improvements in Bumper-Bar Clamps, of which the following is a specification.

This invention relates to automobile bumpers and particularly pertains to means for clamping the bars thereof together.

It is the principal object of the present invention to provide a simple and inexpensive clamp by which two bars, as, for example, bars of an automobile bumper, may be rigidly clamped with their ends in abutting relation to each other and in a manner to insure that the clamp will remain fixed relative to the members upon which it is mounted.

It is another object of the invention to provide a simple structure whereby a suitable and inexpensive finish may be given the clamp.

The present invention contemplates the use of a U-shaped clamping member, adapted to embrace contiguous ends of a pair of bars, said member being provided with means for causing it to rigidly clamp around the ends of the bars, at the same time being held against movement longitudinally of the bars.

The invention is illustrated by way of example in the accompanying drawings, in which:

Fig. 1 is a view in front elevation showing the bumper to which the present invention is applicable.

Fig. 2 is an enlarged fragmentary view in front elevation showing the clamp and the bars to which it is applied.

Fig. 3 is a view in end elevation showing a clamp.

Fig. 4 is a view in section and elevation showing the manner in which the front clamping plate engages the bar.

Referring more particularly to the drawings, 10 and 11 indicate bars of a bumper, which bars are in longitudinal alignment and are disposed in the same plane. It is customary in bumpers of this type to secure the contiguous ends of bars 10 and 11 together by some sort of clamping yoke, but due to the construction of these yokes they

slip longitudinally of the bars and will in some instances move to an ineffective 55 clamping position.

One of the objects of this invention is to permanently locate the clamping device relative to the bars, and for that reason a clamping device 12 is provided having a 60 front plate 13 and a rear plate 14, the front plate being formed with a protrusion 15 which extends between the contiguous ends of the bars as more clearly shown in Fig. 4. The front plate and back plate may, of course, be separate, and if so, it is desirable to form the back plate with overhanging lips 16 by which the space between the body of the two plates will be concealed above and below the bar, thus making the structure more slight and at the same time preventing vertical movement of the clamp. When two separate plates are utilized, bolts 17 and 18 are provided to pass through both plates and are preferably arranged to pass 70 between the adjacent ends of the bars. In the event, however, that the two plates 13 and 14 are formed integral with the upper overhanging portion 16.

It is common practice to apply a trade 80 name or some fanciful design on the front face of the plate 13. This is often made in nickel plate work. In order to economically do this in the present case a face plate 19 is provided to be positioned directly over the 85 face of the front plate 13. This face plate is preferably stenciled and may be nickel plated. If the front face of plate 13 is appropriately painted the nickel plated portion of the plate 19 will cooperate 90 therewith to set out a desired design. This face plate may be used on either form of the invention.

It will thus be seen that by the provision 95 of the present clamp it is possible to rigidly fix the clamping structure relative to the bars to be held, and to thereafter tightly grip the bars to hold them in fixed longitudinal alignment.

While I have shown the preferred form 100 of my invention as now known to me, it will be understood that various changes might be made in the combination, construction and arrangement of parts by those skilled 105 in the art, without departing from the spirit of the invention as claimed.

Having thus described my invention, what I claim and desire to secure by Letters Patent is:

1. A device for clamping abutting bars of 5 automobile bumpers, comprising a plate extending along the aligned faces of the bars on one side and bridging the gap therebetween, said plate being formed with parallel flanges overhanging the edges of the bars, 10 a second plate extending along the aligned faces on the opposite side of the abutting portions of the bars, and clamping means for drawing the two plates together and fastening the contiguous ends of the bars 15 together.
2. A device for fastening the contiguous portions of longitudinally aligned bumper bars together comprising a plate bridging the gap between the contiguous portions of 20 the bars on one side and being formed with marginal flanges between which the bars extend and to which the plate is held against lateral movement, a second plate positioned on the opposite side of the contiguous portions 25 of the bars, and fastening means for clamping the plates together and thus holding the bars.
3. A device for fastening the contiguous portions of longitudinally aligned bumper 30 bars together comprising a plate bridging the gap between the contiguous portions of the bars on one side and being formed with marginal flanges between which the bars extend and to which the plate is held against 35 lateral movement, a second plate positioned on the opposite side of the contiguous portions of the bars, and fastening means for clamping the plates together and thus holding 40 the bars, said fastening means comprising bolts passing between the contiguous ends of the bars to thus prevent longitudinal movement of the clamping plates relative to the bars.
4. A device for fastening the contiguous 45 portions of longitudinally aligned bumper bars together comprising a plate bridging the gap between the contiguous portions of the bars on one side and being formed with marginal flanges between which the bars extend and to which the plate is held against 50 lateral movement, a second plate positioned on the opposite side of the contiguous portions of the bars, fastening means for clamping the plates together and thus hold-

ing the bars, and a protruding member carried by one of the plates to project between and fit into the space between the contiguous ends of the bars for preventing longitudinal movement of the clamping structure relative to the bars.

5. A device for clamping ends of automobile bumper bars together comprising a plate bridging the gap between the ends of said bars and lying against the aligned faces thereof, flange means carried by the plate resting against the edges of the bars to prevent lateral and twisting movement of the plate relative to the bars, another plate lying against the opposite faces of the bars and bridging the gap therebetween, and clamping means for holding the plates and the bars against movement relative to each other.

6. A device for clamping ends of automobile bumper bars together comprising a plate bridging the gap between the ends of said bars and lying against the aligned faces thereof, flange means carried by the plate resting against the edges of the bars to prevent lateral and twisting movement of the plate relative to the bars, another plate lying against the opposite faces of the bars and bridging the gap therebetween, and clamping means for holding the plates and the bars against movement relative to each other, said clamping means comprising bolts passing between the contiguous ends of the bars and having diameters agreeing with the space between said contiguous ends.

7. A device for clamping ends of automobile bumper bars together comprising a plate bridging the gap between the ends of said bars and lying against the aligned faces thereof, flange means carried by the plates resting against the edges of the bars to prevent lateral and twisting movement of the plate relative to the bars, another plate lying against the opposite faces of the bars and bridging the gap therebetween, and clamping means for holding the plates and the bars against movement relative to each other, a protrusion formed as a part of one of said plates, said protrusion projecting between the contiguous ends of the bars and being of a width agreeing with the space between said ends.

ROLLIE B. FAGEOL.
